UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CUSHION.

No. 884,707.

Specification of Letters Patent.

Patented April 14, 1908.

Application filed April 7, 1906. Serial No. 310,461.

To all whom it may concern:

Be it known that I, EDWARD G. BUDD, a citizen of the United States, residing at Philadelphia, in the county of Philadelphia and State of Pennsylvania, have invented certain new and useful Improvements in Cushions, (Case C,) of which the following is a specification.

This invention concerns cushions and refers particularly to cushions for use as backs for seats of the type commonly employed in cars.

The object of the invention is to so improve the construction of seat-back cushions as to increase the strength thereof and to make them more comfortable for occupants of the seat.

In order that the seat shall possess ample strength I employ a frame of metal, this being formed of sheet-metal parts pressed to the desired shape and therefore being comparatively inexpensive. This frame is so constructed as to give to the completed cushion a shape most conducive to the comfort of the occupants of the seat, this being accomplished by the provision of metallic end-form pieces at the ends of the cushion which so shape the covering material as to form a curved body portion and above it a curved head-roll. The usual slats are employed extending across the frame and secured at their ends thereto, and in order to prevent the cushion covering from drawing the end-form pieces inwardly I employ braces secured thereto and to one or more of the transverse slats.

I have illustrated the preferred embodiment of my invention in the accompanying drawings, in which

Figure 1 is a front view of a seat-back cushion, Fig. 2 is an end view of the same, Fig. 3 is a top view of the end of the frame; and Fig. 4 is a section on line 4—4 of Fig. 1.

Referring to these drawings, the frame of the cushion is of rectangular shape and is formed of metallic frame-sections secured together at their ends; the frame may consist of four such sections, but since in seat-back cushions it is desirable to have the upper corners rounded off, I prefer to make the frame from two sections, one, indicated by the numeral 1, constituting the bottom of the frame and the other, 2, bent to form the top and sides. The cross-sectional shape of the frame sections may vary to suit conditions

but is preferably that illustrated in Fig. 4, in which the frame section 2 is shown as consisting of a body portion 3 and flanges 4 and 5 at the sides thereof, the extreme edges of these flanges being curled to provide a smooth edge and to facilitate attaching the covering material thereto. The frame sections are secured together in any suitable manner, as by providing overlapping portions on the flanges and a collar lying between these overlapping flanges into the ends of which the material of the flanges may be sunk. Extending across the frame and secured at their ends to the top and bottom thereof are a plurality of channeled transverse rails or slats 6 which support the usual spiral springs over which the covering is drawn.

At each end of the cushion is an end-form piece 7, which gives shape to the covering of the cushion. This piece is formed of a strip of metal of uniform and substantially U-shaped cross-section, as shown in Fig. 4. The greater portion of the length of this strip is bent in the direction of its length to the arc of a circle and the lesser portion is also curved in a similar manner, the connection between the two arcs being a smooth rounding one. The shape of the end-form piece is best shown in Fig. 2, in which it will be seen that it has a large curved portion for the body of the cushion and a small curved portion for the head-roll. Each of the two end-form pieces is secured upon one of the end members of the frame with the bottom of the U outwards by rivets 8 at the ends of the piece and at the junction of the body and head-roll portions. When the frame is constructed as shown in the drawings to provide rounded upper corners, the upper ends of the pieces 7 are curved laterally as shown in Figs. 1 and 3 to conform to the shape of the rounded corners and may be cut away somewhat on the inside of this curve, as indicated at 9 (Fig. 1) to facilitate securing its upper end to the frame. In order to stiffen the construction and hold the pieces 7 against being pulled laterally by the covering, I provide angular braces 10 arranged to transmit a portion of the strain on the end-form pieces to one or more of the slats 6. These braces may be sheet-metal strips flanged at the edges to give them greater strength and having feet at the ends perforated to receive rivets. One end of each of these braces is secured to the end slat 6 and the other to the end-form

2
piece 7, the point of connection of the brace to the latter being near the top of the curve of the body portion. Of course, if desired more than one brace may be used at each end of the cushion.

5 With the frame constructed in this manner, the spiral springs are secured upon the slats 6 and flat springs are supported on these spiral springs in the usual manner. The 10 covering material is then drawn over these springs and the end-form pieces 7, its edges being drawn down tightly and secured to the frame. It will be seen that the pieces 7 give shape to the covering and cause it to form a body portion and a head-roll, the shape 15 which has been found to contribute most to the comfort of occupants of a seat. A frame constructed from metallic parts in the manner described possesses ample strength and the addition of the braces 10 stiffens the 20 structure at points where displacement would be apt to occur. The U-shaped cross-sectional shape of the end-form pieces and mounting them with the bottom of the U 25 outwards affords a wide support for the covering at the ends of the frame and one which avoids the danger of the pieces cutting through the fabric along the edges of the cushion.

30 Having now described my invention, what I claim as new therein and desire to secure by Letters Patent is as follows:—

1. In a cushion, a frame comprising metallic frame sections secured together at their 35 ends, and metallic end-form pieces curved in the direction of their length secured to the ends of said frame, substantially as set forth.

2. In a cushion, a frame comprising metallic frame sections secured together at their 40 ends, and end-form pieces formed of metal strips of uniform cross-section, each of said strips being curved in the direction of its length to form a body portion and a head-roll and each secured to said frame along one 45 end thereof, substantially as set forth.

3. In a cushion, a rectangular frame comprising two metallic frame sections secured together at their ends, one forming the bottom of the frame and the other bent to form 50 the top and ends and having rounded corners, and metallic end-form pieces curved in the direction of their length secured to the ends of said frame, each of said pieces being bent laterally at its upper end to conform to the rounded corner of the frame, substantially 55 as set forth.

4. In a cushion, a rectangular metallic frame and form-pieces of sheet metal secured to the ends of the frame and shaped to provide surfaces thereon curved in the direction 60 of the length of the pieces to form a body portion and a head-roll, substantially as set forth.

5. In a cushion, a rectangular metallic frame and form-pieces of sheet metal secured 65

to the ends of the frame, said pieces being flanged inwardly of the frame at their edges and shaped to provide surfaces thereon curved in the direction of the length of the pieces to form a body portion and a head-roll, substantially as set forth. 70

6. In a cushion, a frame consisting of metallic frame sections secured together at their 75 ends and metallic end-form pieces of U-shaped cross-section curved in the direction of their length and secured along the ends of the frame with the bottom of the U outwards, substantially as set forth.

7. In a cushion, a frame comprising metallic frame sections secured together at their 80 ends and end-form pieces formed of metal strips of uniform U-shaped cross-section, each of said strips being curved in the direction of its length to form a body portion and a head-roll and each secured to said frame 85 along one end thereof with the bottom of the U outwards, substantially as set forth.

8. In a cushion, a rectangular frame comprising two metallic frame sections secured together at their ends, one forming the bottom of the frame and the other bent to form the top and ends and having rounded corners and metallic end-form pieces of U-shaped cross-section and curved in the direction of their length to form a body portion and a 95 head-roll, each of said pieces being secured along one end of the frame with the bottom of the U outwards and each bent laterally at its upper end to conform to the rounded corner of the frame, substantially as set forth. 100

9. In a cushion, a frame comprising metallic frame sections secured together at their ends, slats extending across and secured at their ends to said frame, end-form pieces curved in the direction of their length secured to the ends of said frame, and means 105 for bracing said pieces upon said slats, substantially as set forth.

10. In a cushion, a frame comprising metallic frame sections secured together at their 110 ends, end-form pieces formed of metal strips of uniform cross-section, each curved in the direction of its length to form a body portion and a head-roll and each secured to said frame along one end thereof, slats extending across and secured at their ends to said frame and braces each secured to one of said pieces and one of said slats, substantially as set forth. 115

11. In a cushion, a rectangular frame comprising two metallic frame sections secured together at their ends, one forming the bottom and the other bent to form the top and ends and having rounded corners, slats extending across and secured at their ends to 120 said frame, metallic end-form pieces curved in the direction of their length to form a body portion and a head-roll and secured along one end of said frame, each of said pieces being bent laterally at its upper end to 125

130

conform to the rounded corner of the frame, and braces each secured at one end to the body portion of one of said pieces and at the other end to one of said slats, substantially as set forth.

12. In a cushion, a frame consisting of metallic frame sections secured together at their ends, metallic slats extending across and secured at their ends to said frame, metallic end-form pieces of U-shaped cross-section curved in the direction of their length and secured along the ends of the frame with the bottom of the U outwards, and braces secured to said pieces and said slats, substantially as set forth.

13. In a cushion, a rectangular metallic frame and form-pieces of sheet-metal secured to the ends of the frame, said pieces being flanged inwardly of the frame at their edges

and said flanges being curved in the direction of the length of the pieces, substantially as set forth.

14. In a cushion, a rectangular metallic frame, slats extending across the frame, form-pieces of sheet-metal secured to the ends of the frame, said pieces being flanged inwardly of the frame at their edges, and said flanges being curved in the direction of the length of the pieces, and means for bracing said form-pieces upon said slats, substantially as set forth.

This specification signed and witnessed this 31st day of March, 1906.

EDWARD G. BUDD.
